(57) **CLAIM**

The ornamental design for a laminator, as shown and described.

DESCRIPTION

FIG. 1 is an elevated perspective view of the laminator of the claimed invention

FIG. 2 is a front view of the laminator shown in FIG. 1;

FIG. 3 is a back view of the laminator shown in FIG. 1;

FIG. 4 is a right side view of the laminator shown in FIG. 1;

FIG. 5 is a left side view of the laminator shown in FIG. 1;

FIG. 6 is a top view of the laminator shown in FIG. 1; and,

FIG. 7 is a bottom view of the laminator shown in FIG. 1. Features shown in broken lines in the drawings are not part of the claim.
